STOKER FURNACE

Herbert E. Preston, Philadelphia, Pa., assignor to
American Engineering Company, Philadelphia,
Pa., a corporation of Pennsylvania

Application December 18, 1931, Serial No. 581,948

5 Claims. (Cl. 110—75)

This invention relates to improvements in
stoker furnaces, and has a particular application
to furnaces employing multiple retort underfeed
stokers of the class disclosed in U. S. Patent No.
1,443,202.

5 A principal object of the invention is to pro-
vide novel and improved means for maintaining
the furnace wall surface, and particularly the
surfaces abutted by or adjacent to the fuel-bed,
10 relatively free from adhesions of fused particles
of refuse either originating in the fuel-bed or
flowing down the wall from above the fuel-bed
in the form of slag.

15 A more specific object of the invention is to
provide means for maintaining between the fuel-
bed and the adjacent wall surfaces and in the
areas of maximum clinker formation a screen
of air or other gas tending to prevent clinker
adhesion or so modifying the physical character-
20 istics of the clinkers as to render them readily
removable by the abrasive action of the moving
fuel over the wall surface.

25 The invention further contemplates the pro-
vision in a furnace side wall of a novel nozzle
construction highly effective for the aforesaid
purposes.

30 The invention further resides in certain novel
structural details and arrangements hereinafter
set forth and illustrated in the attached draw-
ings, in which:

35 Figure 1 is a side elevational and partial sec-
tional view showing the side wall of a stoker
furnace of the type set forth embodying my in-
vention;

Fig. 2 is a section on the line 2—2, Fig. 1;

Fig. 3 is an enlarged fragmentary sectional
view corresponding to Fig. 2 illustrating certain
details of the construction;

Fig. 4 is a section on the line 4—4, Fig. 1;

Fig. 5 is a section on the line 5—5, Fig. 1;

40 Figs. 6 and 7 are perspective views respectively
showing the reverse sides of one of the nozzle
elements;

Fig. 8 is a sectional view of a portion of the
45 nozzle assembly taken on the line 8—8, Fig. 1;

Fig. 9 is a front elevational view of the upper
terminal section of the box;

Fig. 10 is a lower end elevation of the struc-
ture shown in Fig. 9;

50 Fig. 11 is a section on the line 11—11, Fig. 9;

Figs. 12 and 13 are respectively front and end
elevational views of the terminal nozzle; and

Fig. 14 is a section on the line 14—14, Fig. 12.

With reference to Fig. 1 of the drawings, 1 is
55 the side wall of a multiple retort underfeed stoker

furnace, the tuyère line of the furnace defining
the stoker grate being indicated at 2 in broken
lines. A wind-box, the lower portion of which
is shown at 3, is provided below the stoker grate,
from which box air passes to and through the
5 tuyères to the fuel-bed in well known manner.

In accordance with my invention, I provide
the side wall 1 of the furnace with a passage or
duct 5, this passage at its upper end and as
shown in Fig. 1 extending substantially the full
10 length of the stoker grate structure, the terminal
walls of the passage 5, shown in Fig. 1 in broken
lines, being indicated by the reference numeral
6. As therein illustrated, the passage 5 extends
upwardly in the wall to a point in the present in-
stance somewhat above the line of the tuyères 2.
The end walls 6 of the passage 5 converge down-
wardly, and the lower end of said passage com-
municates with an opening 7 in the inner por-
tion of the wall 1, this opening as shown in Fig. 20
4 being connected with the interior of the wind-
box through a suitable duct 8. This duct has
a branch 9, the function of which will be here-
inafter described. A valve 10 in the duct 8 con-
trols the opening 7, and valves 12 and 13 con-
25 trol the branch 9 and that portion of the duct
8 which extends to the wind-box. As shown
in Fig. 5, the portions of the wall forming the
opposite faces of the passage 5 may be united
by tie plates or anchors 5a.

30 Set into the wall 1 and in the present instance
co-extensive with the upper end of the passage 5
is a metallic or other suitable box 15, this box
having in its bottom wall a longitudinal opening
16 communicating directly with the passage 5. 35
The inner side of the box 15 is open to the in-
terior of the furnace, the box thereby forming
a recess in the side wall 1 which extends longi-
tudinally of the grate structure of the stoker
and somewhat above the upper surface of the 40
latter. The box 15 in the present instance is so
formed and so arranged within the wall 1 that
the recess in said wall formed thereby lies some-
what below the upper surface of the fuel-bed and
conforms to the fuel-bed contour. Preferably, 45
the box is made in longitudinal sections, and in
the embodiment illustrated in Fig. 1, two such
sections are shown, the upper being curved and
the lower adjoining section being straight. This
provides for standardization of the boxes while
50 meeting the requirements of furnaces of differ-
ent sizes. For installations of greater length,
the box may be terminated at its lower end by a
curved section (see broken lines Fig. 1) which
may correspond to the upper curved section in 55

the reverse position; and if still greater length is required an additional straight section, or sections, may be inserted.

At its inner edges and as best shown in Fig. 3, 5 the box 15 is provided with depending and up-standing flanges, 17 and 18 respectively, which constitute retaining means for a series of nozzle elements 19. A preferred form of these elements is illustrated in Figs. 6, 7 and 8. As therein illustrated, each comprises a pair of rearwardly extending arms 21 and 22, the outer ends of which are offset to provide shoulders which interlock with the flanges 17 and 18 of the box 15 to retain the elements in the latter. Joining the inner 10 ends of the arms 21 and 22 is an arcuate body portion 23, which portion is dished or formed at an angle to the plane of the said arms. At the upper end and at one side of the body portion 23 is a lug 24, and at the opposite end is a corresponding and somewhat larger lug 25. These lugs in effect form spacing elements for the body portions of the adjoining elements and define between their inner faces the nozzle apertures through which the boxes 15 are in communication 15 with the interior of the furnace. The upper face of each of the lugs 25 forming the bottom of the nozzle aperture is in the present instance substantially horizontal; while that face of the lug 24 forming the top of the aperture is beveled upwardly and outwardly. In the present instance, 20 the nozzles are positioned in the box with the side thereof containing the lugs 24 and 25 toward the rear wall 26 of the furnace, and the formation of the body portion 23 of the nozzle elements 25 and of the lugs 24 and 25 is such that air or other gas passing from the box 15 into the interior of the furnace is projected fan-like upwardly and rearwardly along the surface of the wall 1, the jets of air from the various nozzle 25 openings forming in effect a screen of gas between the wall surface and the fuel-bed and over the adjoining wall areas. The relative arrangement and form of the nozzle openings are well illustrated in Fig. 8.

40 The nozzle elements 18 are readily inserted in the boxes by passing the arms 21 and 22 inwardly through the opening between the flanges 17 and 18, and thereafter turning the elements angularly to bring the arms into interlocking engagement with the said flanges, as illustrated in Fig. 3.

Since a full complement of nozzle elements could not thus be inserted in the boxes, I provide a terminal nozzle of special design illustrated in Figs. 12 and 13. At one end surface the body portion of this nozzle 31 is shaped correspondingly with the other nozzle elements, but the body portion is elongated and is held in the box not by means of interlocking shoulders but by a bolt 30 which passes through an elongated opening 32 in the nozzle and through a suitable lug 33 formed in the box. Preferably the head of the bolt is confined within a recess 34 in the said lug to prevent the bolt from turning. The elongated opening 32 provides for movement of the block 31 in expansion and contraction of the series of nozzle elements, and it will be noted that in the present instance the said opening 32 is formed in the bottom of a recess 35 which provides for packing a refractory material around the nut to protect the latter.

70 Preferably, as illustrated in Fig. 9, the box 15 is provided with partitions 15^a which divide said box into separate compartments, which provides

for zoning or limiting the supply of air or gas to different groups of nozzles. For this purpose and as illustrated in Fig. 3, I may provide suitable steel or other plates 36 which may be secured in the bottom of the box so as to 5 block off any desired portion of the bottom opening 16 of the individual compartments.

To facilitate the installation of the box 15 in the wall of the furnace where, as in the illustrated embodiment, the said box extends at an 10 angle to the horizontal, I may provide the top and bottom walls of the box with a series of brackets 38 which may be secured to the box by bolts or in any other convenient manner, these 15 brackets providing horizontal and vertical surfaces for abutment with the bricks of the said wall. The brackets 38 obviously may be formed as integral parts of the box structure.

In Fig. 4, I have illustrated means whereby the passage or duct 5 may be connected to the 20 wind-box 3 of the stoker, this connection providing for diversion of a portion of the combustion air to the box 15. As previously set forth, I also provide an independent duct 9 for directing to the box 15 air or gas from other sources, 25 such, for example, as inert flue gases of the furnace or oxygen. Use of the stack gases has the effect of cooling without materially increasing the rate of combustion of the fuel adjoining the side walls; and it has been found that oxygen 30 projected through the nozzles from the box 15, by increasing the rate of combustion in the affected areas, tends to burn or melt the clinker, which then drips into the fuel bed to be carried off with the ash.

In a stoker furnace of the type set forth, the point of inception of clinker formations on the walls is slightly below the top of the fuel-bed, and clinkers forming and growing in this area unchecked interfere materially with the normal 40 fuel-feeding function and consequently with the efficiency of the stoker and the furnace as a whole. By maintaining a screen of a fluid medium over the wall surface embracing the said points of inception, the formation of clinkers may be prevented or minimized, and by confining the fluid to the wall surface and to the stated areas, the desired result may be accomplished with little or no interference with the normal combustion process. The aforescribed construction accomplishes the desired result, the fluid being directed 45 upwardly and laterally from a point corresponding with or slightly below the clinker-inception area but well above the bottom of the fuel bed. A single row of nozzles placed as described above 50 somewhat below the upper surface of the fuel-bed and adapted to project the fluid upwardly and preferably toward the rear wall of the furnace and over the surface of the side wall has been found entirely effective.

It will be apparent that there may be considerable modification without departure from the underlying principles of the invention.

I claim:

1. In a device of the character described, the 65 combination with a furnace wall having a relatively narrow passage therein extending below the points of maximum clinker formation, and terminating in the inner surface of said wall, of a plurality of nozzle elements detachably mounted 70 in said terminal end in side-by-side relation, and lugs on the sides of said nozzle elements to retain them in spaced relation, said nozzles having their oppositely arranged faces beveled and forming therebetween nozzle openings inclined to the face 75

of the wall through which a gaseous medium may be ejected from the passage over the inner surface of said wall embracing the points of maximum clinker formation.

5 2. A nozzle element adapted for assembly in side-by-side relation with similar elements to form a nozzle structure, said element having a body portion substantially in the form of a dished segment, a lug at the top and bottom of said body portion respectively, said lugs constituting spacers which in assembly form the upper and lower edges of nozzle openings between the sides of the adjoining elements, the said bottom lug having an upper surface extending in assembly in a substantially horizontal direction, and the upper lug having an upwardly and outwardly beveled face defining the upper edge of said nozzle opening whereby a gas ejected through said openings is directed transversely and upwardly from the forward face of the nozzle assembly.

3. A nozzle element adapted for assembly in side-by-side relation with similar elements to form an elongated nozzle structure, said element having a body portion in the form substantially of a dished segment, nozzle-retaining elements projecting from the rear edge of said body portion, lugs projecting from a side surface of said body portion at top and bottom of the latter and in assembly defining the upper and lower edges of nozzle openings formed between said elements, that surface of at least one of said lugs which defines the edge of said opening being beveled and diverging outwardly from the opening-defining surface of the other lug.

35 4. In a device of the character described, the combination with a furnace wall having a relatively narrow passage terminating in the inner surface thereof, the terminal end of said passage being formed on a line having adjoining straight and curved portions so arranged that they con-

form substantially with the normal fuel bed contour, of a box mounted in said wall and defining the terminal end of said passage, said box having straight and curved sections corresponding to the straight and curved sections of the passage, a plurality of nozzle elements detachably mounted in said box at the terminal end of said passage in side by side relation, and lugs on the sides of said nozzle elements to retain them in spaced relation, said nozzles having their oppositely arranged faces beveled and forming therebetween nozzle openings inclined to the face of the wall through which a gaseous medium may be ejected from the passage over the inner surface of said wall embracing the points of maximum clinker formation.

5 5. In a device of the character described, the combination with a furnace wall having a relatively narrow passage therein extending below the points of maximum clinker formation and terminating in the inner surface of said wall, of a plurality of nozzle elements mounted in side by side relation in the terminal end of said passage, lugs on the sides of said nozzle elements to retain them in spaced relation, said nozzle elements having their oppositely arranged faces beveled and forming therebetween nozzle openings, for directing a cooling medium, such as air, over the inner surface of the wall embracing said points of maximum clinker formation, interlocking means in said passage and on said nozzle elements for securing the latter in said passage by an angular movement of the nozzle elements following insertion thereof in the end of the passage, a terminal nozzle, and independent fastening means for said terminal nozzle adapted for manipulation following insertion of said nozzle in the end of said passage to secure the nozzle in position.

HERBERT E. PRESTON.
